UNITED STATES PATENT OFFICE

131,298

DESIGN FOR A LABEL FOR A TOY MOTOR MOUNTING OR SIMILAR ARTICLE

Harry D. Finberg, Boston, Mass.

Application August 18, 1941, Serial No. 102,912

Term of patent 14 years

To all whom it may concern:

Be it known that I, Harry D. Finberg, a citizen of the United States, residing at Boston, in the county of Suffolk and Commonwealth of Massachusetts, have invented a new, original, and ornamental Design for a Label for a Toy Motor Mounting or Similar Article of which the following is a specification, reference being had to the accompanying drawing, forming part thereof.

The figure is a plan view of a label for a toy motor mounting or similar article showing my new design.

The article is of no appreciable or substantial thickness and no features of the design project from the surface.

I claim:

The ornamental design for a label for a toy motor mounting or similar article, as shown and described.

HARRY D. FINBERG.
